HIGH-FREQUENCY OSCILLATOR

John F. Farrington, Flushing, N. Y., assignor to
Hazelton Corporation, a corporation of Delaware

Application February 16, 1937, Serial No. 125,969

12 Claims. (Cl. 250—36)

This invention relates to high-frequency signaling systems, and more particularly to improvements in tunable oscillation systems or coupling systems useful in such signaling systems.

5 Conventional high-frequency signaling systems generally comprise two or more tunable systems, such as oscillation or coupling systems, having adjustable tuning elements ganged together for unicontrol operation, whereby the systems may be tuned over the same or different frequency ranges. In the case of a superheterodyne wave-signal receiver, one oscillation system is associated with a vacuum tube to form a local beat-frequency oscillator, the oscillation frequency being maintained at a fixed frequency difference with respect to that of the other tunable systems, such as the signal-selector systems, of the receiver. The adjustable tuning elements of such systems are usually variable capacitance elements. However, as pointed out in the copending application of Harold A. Wheeler and John F. Farrington, Serial No. 125,968, filed Feb. 16, 1937, certain definite advantages are attendant upon inductance tuning of the selector and oscillator 15 frequency-determining circuits, particularly when it is desired to tune over a wide range of frequencies. One of the important advantages concerns the resonance gain of such a system as determined by the anti-resonant impedance thereof, it being possible to maintain a maximum anti-resonant impedance and, as a consequence, a higher resonance gain throughout the tuning range when inductance tuning is used.

In the aforementioned copending application, 20 the advantages of inductance tuning of the various tunable circuits are realized by providing a tunable system including an inductance tuning unit of novel construction and arrangement. Briefly, the tuning unit comprises a winding and a nonmagnetic conductive shield relatively movable with respect to each other into and out of coupling relationship and so related in configuration that there is procured the closest coupling therebetween consistent with the avoidance of frictional contact and excessive capacitance.

While this form of tuning unit is particularly desirable for the application specified, it gives rise to certain additional problems, particularly in the construction of an oscillation or coupling system having a satisfactory frequency-response characteristic. More specifically, difficulties arise in obtaining a transfer circuit between the input and output circuits of the system which will ensure an output voltage of substantially uniform amplitude at all frequencies within the tuning

range. These difficulties arise primarily in obtaining satisfactory coupling between the transfer circuit and the tunable frequency-determining circuit and, further, in compensating for the variations in the output voltage, particularly at 5 one end of the tuning range, occasioned by variations in the anti-resonant impedance of the frequency-determining circuit.

It is an object of the present invention, therefore, to provide an oscillation system, tunable 10 over a wide frequency range by variable inductance means included in the frequency-determining circuit, which operates in a manner such that the frequency-response characteristic thereof is approximately uniform at all frequencies within 15 the range.

More specifically, it is an object of the invention to provide an oscillator including an oscillation system of the above general arrangement in which the effective coupling between the energy 20 transfer circuit and the frequency-determining circuit is independent of frequency and the characteristics of the transfer circuit are such as to compensate for tendencies toward output voltage variations occasioned by variations, with frequency, of the antiresonant impedance of the 25 frequency-determining circuit.

In brief, the above objects are attained in accordance with the present invention by providing a tunable oscillation system comprising a pair of 30 input terminals, a pair of output terminals, a frequency-determining circuit connected to one of the pairs of terminals and including an adjustable inductance tuning unit, which may be of the type described briefly above and described in detail and claimed in the copending application referred to above, and a transfer circuit inductively coupled to said frequency-determining circuit and connected to the other of said pairs of terminals. In the preferred embodiment, the transfer circuit is coupled to a fixed inductance element, connected in parallel with the adjustable inductance tuning unit and, with suitable capacitance means, forming the frequency-determining circuit. In order to compensate for tendencies 40 toward variations in output voltage with variations of the antiresonant impedance of the frequency-determining circuit, the transfer circuit is so proportioned that its responsiveness varies with frequency, at the affected end of the tuning 45 range, in a sense to provide the desired compensation. More particularly, this circuit is designed to be resonant at a frequency in the vicinity of, but above the upper limit of the tuning range, so that the tendency toward a decrease in 50

output voltage at the high-frequency end of the tuning range, normally resulting from such variation in impedance is compensated for by the increased resonance gain in the transfer circuit.

- 5 In a superheterodyne receiver, where it is necessary to align one tunable circuit of the type described, as that of the local oscillator, to operate at a fixed frequency difference with respect to one or more additional circuits tunable by 10 similar adjustable inductance elements over a wide tuning range, the fixed inductance element in parallel with the tuning unit may also comprise a part of the aligning means, simulating the function of the conventional series-padding condenser used in capacitance tuned circuits.

15 The novel features believed to be characteristic of the invention are set forth with particularity in the appended claims. The invention itself, however, both as to its organization and method 20 of operation, together with further objects and advantages thereof, will best be understood by reference to the specification taken in connection with the accompanying drawing, in which Fig. 1 shows the application of the invention to a 25 tunable coupling stage, while Fig. 2 illustrates the invention as applied to a local beat-frequency oscillator of a high-frequency signal-receiving system of the superheterodyne type.

Referring now more particularly to the drawing, Fig. 1 illustrates a tunable oscillation system embodying the invention utilized to couple an antenna circuit to the first vacuum tube amplifier of a high-frequency signal receiver, while Fig. 2 is a circuit diagram, partly schematic, of a receiver of the superheterodyne type having embodied therein a local oscillator constructed and arranged in accordance with the present invention.

Referring particularly to Fig. 1 of the drawing, 40 there is shown a tunable oscillation system comprising input terminals 1 connected to an antenna-ground circuit and output terminals 2 coupled to the input circuit of a vacuum tube 8 through a high-frequency by-pass condenser 9, 45 the output circuit of the tube 8 being coupled to a signal-translating system, which may comprise a conventional radio receiver. The oscillation system comprises a frequency-determining circuit connected to the output terminals 2 and 50 including an adjustable inductance element 5, which may be constructed and arranged in accordance with the invention of the aforesaid pending application, connected in parallel with a fixed inductance element 1 and a condenser 6, 55 shown as a fixed condenser though in some cases it may also be variable. There is also provided a transfer circuit connected to the input terminals 1 and comprising an inductance element 3 coupled to the fixed inductance element 1 of 60 the frequency-determining circuit and having a condenser 4 connected in parallel therewith to tune the transfer circuit outside of, preferably above, the tuning range of the system. As indicated, a source of control bias may be connected 65 to the grid of the tube 8 to control its amplification in a conventional manner.

The advantages of using an adjustable inductance unit to tune a tunable system over a wide frequency range have been pointed out above. 70 However, as was noted above, when this form of tuning is employed, certain difficulties, pertaining particularly to the coupling of the transfer circuit to the frequency-determining circuit and the variation in voltage across the latter circuit 75 occasioned by variation in its antiresonant im-

pedance, must be overcome if the system is to have a fairly uniform output voltage over the entire tuning range. In regard to the first of these difficulties, the impracticability of attempting to couple the inductance element 3 to the 5 adjustable inductance element 5 to secure coupling therewith, independent of any adjustment of the latter element, is readily apparent.

In accordance with the present invention, coupling between the transfer circuit 3, 4 and the 10 frequency-determining circuit 5, 6, 7 which is independent of frequency and the adjustment of the inductance element 5 is obtained by connecting the fixed inductance element 1 in parallel with the other elements of the frequency-determining circuit and inductively coupling thereto the element 3 included in the transfer circuit, thus forming, in effect, a transformer. As is well known, the voltage transformation ratio of this form of transformer is independent of frequency 20 so that the ratio of the voltage induced across the element 3 to that across the circuit 5, 6, 7 is independent of frequency and it may be said that the effective coupling between the transfer circuit and the frequency-determining circuit is approximately constant over the tuning range.

It is known that the losses in such a tunable system are such that the antiresonant impedance of the resonant circuit tends to decrease with increasing frequency, so that the voltage across 30 the system tends to decrease with increasing frequency. In conventional arrangements this effect is too small appreciably to reduce the voltage across the frequency-determining circuit. With the arrangement shown, however, the decrease 35 in antiresonant impedance with frequency is exaggerated by the adjustment of the inductance thereof to increase the frequency of the system. As a result, the decrease in voltage across the output of the tunable system at the high-frequency 40 end of the tuning range becomes very considerable.

In accordance with the present invention, the problem outlined above is overcome by tuning the transfer circuit comprising the inductance 45 element 3 and condenser 4 to resonance at a frequency in the vicinity of, but above, the upper limit of the tuning range. As a result, the increase in the resonance gain of the transfer circuit compensates for the tendency of the voltage 50 across the output circuit of the tunable system to decrease as the system is tuned to frequencies approaching the upper limit of the tuning range. In other words, the increase in resonance gain with frequency effectively increases the transformation ratio between the voltage across the inductance element 7 and the voltage applied to the input terminals 1, so that the output voltage at the terminals 2 is rendered more nearly uniform throughout the tuning range.

60 Referring now to Fig. 2 of the drawing, there is shown a complete superheterodyne receiver having the present invention embodied in the oscillation system of the local beat-frequency oscillator. While the receiver shown is described 65 more particularly with reference to its use in the reception of sound signal-modulated carriers, it will be understood that it may be used for the reception of television signal-modulated carriers by modification of conventional elements 70 thereof. Briefly described, the receiver comprises a tunable radio-frequency amplifier 10 having its input circuit coupled to an antenna-ground circuit 11 and its output circuit coupled to the input circuit of a tunable frequency changer 75

or modulator 12. The radio-frequency amplifier 10 and the frequency changer 12 are entirely conventional in form with the exception that the tunable circuits thereof include adjustable inductance tuning units as the variable reactance element thereof. Coupled in cascade with the frequency changer 12, in the order named, are an intermediate-frequency amplifier 13, a detector and source of automatic amplification 14, a signal-frequency amplifier 15, and a translating device 16 indicated as a sound reproducer.

Also coupled to the input circuit of the frequency changer 12, by means comprising a condenser 17, is a local beat-frequency oscillator constructed and arranged in accordance with the present invention and indicated generally at 18. This oscillator comprises a shielded vacuum tube 20, preferably a pentode, having its input and output electrodes coupled to a tunable system 21 connected to terminals 2, corresponding to the terminals 2 of Fig. 1, though in this case they are connected as input terminals, being connected to the output electrodes of the tube 20. Preferably, the tube 20 is of a type having minimum inherent capacitance between its electrodes and lead-in wires. As indicated, adjustment of the resonant frequency of the system 21 over the desired tuning range is accomplished by varying the inductance of an adjustable inductance 22, which may be constructed and arranged in accordance with the invention disclosed in the aforesaid application, connected in parallel with a fixed inductance element 23 and fixed capacitance means 24. The capacitance means 24 may comprise only the output capacitance of the tube 20 and the stray lead capacitances, all effectively in series with the direct current blocking condenser 25. The energy transfer circuit coupled between the input electrodes of the tube 20 and the frequency-determining circuit 21 comprises essentially the inductance element 26 coupled to the inductance element 23 and the capacitance 30 consisting of the grid-cathode capacitance of the tube 20 and stray lead capacitance. There is also connected in this circuit a grid-leak resistor 27 which is shunted by a high-frequency bypass condenser 28. The transfer circuit is connected between the terminals 1, corresponding to the terminals 1 of Fig. 1, but in this case effectively constituting output terminals of the oscillation system.

Additional features of the circuit include the complete shielding of the elements of the oscillator 18, as indicated by the dashed line 19; the application of operating voltages of appropriate value to the screen and anode electrodes of the oscillator tube through the +B terminal and appropriate voltage dropping resistors; the connection of the tuning units of the several tunable circuits included in the amplifier 10, the frequency changer 12, and the oscillator 18 for unicontrol adjustment, as indicated by the dotted line U; and the provision of an automatic amplification control circuit including the connection 29 for deriving from the detector 14 a bias voltage variable with the signal-carrier amplitude and applying the same negatively to the input electrodes of one or more of the tubes included 70 in the radio-frequency amplifier 10 and the intermediate-frequency amplifier 13 to maintain the signal output within a narrow range for a wide range of signal-input amplitudes.

The receiver, as generally described above, is 75 of the conventional superheterodyne type, the

operation of which is well understood in the art. Briefly, a desired signal-modulated carrier intercepted by the antenna circuit 11 is selected and amplified in the radio-frequency amplifier 10, is further selected and converted into a modulated intermediate-frequency signal in the modulator or frequency changer 12, is further selected and amplified by the intermediate-frequency amplifier 13, and is supplied to the detector 14 for rectification. The modulation-frequency components are derived by the detector 14 and are amplified in the signal-frequency amplifier 15 and supplied to the translating device 16 for reproduction. The amplitude of the input voltage to the detector 14 is maintained within narrow 15 limits through the action of the automatic amplification control circuit in the manner well understood in the art.

As in the arrangement of Fig. 1, by coupling the inductance element 26 of the transfer circuit to the fixed inductance element 23 of the frequency-determining circuit there is procured an effective coupling to the oscillation circuit, tunable by an adjustable inductance element, which is substantially constant over the tuning range 25 of the system, while, by tuning the transfer circuit 26, 30 above the upper limit of the tuning range, variations in the antiresonant impedance of the frequency-determining circuit 21 are approximately compensated, thereby imparting an 30 approximately uniform output voltage characteristic to the oscillator 18 throughout its tuning range.

As mentioned above, an additional feature of the invention concerns the use of the inductance element 23 as a portion of the aligning means for maintaining frequency alignment between the frequency-determining circuit 21 of the oscillator 18 and the tunable systems embodied in the amplifier 10 and the frequency changer 12. 40 Thus, the tunable input circuit of the amplifier 10 and the frequency-determining circuit 21 comprise a pair of circuits tunable to different frequencies and over different frequency ranges, and it is conventional practice to align these 45 circuits so that the frequency difference thereof is maintained approximately constant over their respective tuning ranges. This is usually accomplished in conventional arrangements employing variable capacitance tuning by using series- and 50 parallel-padding condensers in one or more of the circuits. In an arrangement of the form described, however, wherein inductance tuning is employed, alignment may be secured by adjusting the inductances of the circuits. The inductance element 23 may conveniently be used for this purpose by properly proportioning the inductance thereof relative to the inductance of the tunable circuits with which the circuit 21 is to be aligned and constructing the element so 55 that its inductance may be adjusted within sufficiently wide limits to permit alignment of this circuit with the other circuits. In the arrangement described, also the parallel capacitance is 60 preferably given a value different than that of the other tunable circuits with which the oscillator is to be aligned, by analogy to the use of the inductance elements of different inductance value in conventional variable capacitance tuning arrangements.

While it will be understood that the circuit specifications of the oscillator 18 may vary according to the design of any particular application, the following circuit specifications for an oscillator employed for the application described 75

are included, by way of example only, using an acorn tube of the 954 type:

Radio-frequency tuning range	58-100 megacycles.
Condenser 25	.002 microfarad.
Condenser 24 (total effective shunt capacitance of the circuit 21).	7 micro-microfarads.
Condenser 28	75 micro-microfarads.
Condenser 30	3 micro-microfarads.
Resistor 27	10,000 ohms.
Winding 22	7 turns No. 26 D. S. C. single layer close wound on a cylindrical form $19\frac{1}{2}$ inch diameter over a commutated iron core. Maximum inductance 1.4 microhenries.
10	16 turns No. 26 D. S. C. single layer close wound on $\frac{1}{2}$ inch Bakelite rod. Inductance 3.8 microhenries.
Inductance element 23	24 turns No. 26 D. S. C. single layer close wound on the same Bakelite rod as inductance element 23 with the adjacent low potential ends of the two elements spaced one turn apart.
15	Inductance element 26

- 20 The shield for varying the inductance of the element 22 comprises a brass member having a conically shaped inner surface relatively movable in telescoping relationship to the turns of this element.
- 25 While there have been described what are at present considered to be the preferred embodiments of the invention, it will be understood that various changes and modifications may be made therein without departing from the invention, and it is contemplated in the appended claims to cover all such changes and modifications as fall within the true spirit and scope of the invention.

What is claimed is:

- 35 1. A tunable coupling system comprising a pair of input terminals, a pair of output terminals, a frequency-determining circuit connected to one of said pairs of terminals including a pair of inductance elements and fixed capacitance means, all effectively in parallel, one of said inductance elements being adjustable to vary the frequency of said circuit continuously over a wide range, and a transfer circuit connected to the other of said pairs of terminals and including a third inductance element coupled to the other of said 40 pairs of inductance elements.
- 45 2. A tunable coupling system comprising a pair of input terminals, a pair of output terminals, a frequency-determining circuit connected to one of said pairs of terminals including a pair of inductance elements and fixed capacitance means, all effectively in parallel, one of said inductance elements being adjustable to vary the frequency of said circuit continuously over a wide range, and a transfer circuit connected to the other of said pairs of terminals and including a third inductance element coupled to the other of said 50 pair of inductance elements, said transfer circuit being resonant at a fixed frequency outside of said frequency range.
- 55 3. A tunable coupling system comprising a pair of input terminals, a pair of output terminals, a frequency-determining circuit connected to one of said pairs of terminals including a pair of inductance elements and fixed capacitance 60 means, all effectively in parallel, one of said inductance elements being adjustable to vary the frequency of said circuit continuously over a wide range, and a transfer circuit connected to the other of said pairs of terminals and including a third inductance element coupled to the other of said 65 pair of inductance elements, and capacitance effective to tune said third inductance element to a frequency in the vicinity of the highest frequency of said range.
- 70 4. An oscillator comprising a vacuum tube including input and output electrodes, a frequency-determining circuit coupled to one of said electrodes, said circuit including parallel-connected fixed capacitance means and at least one inductance element adjustable to vary the frequency of said circuit continuously over a wide range, said frequency variations incidentally varying the parallel impedance of said circuit to an extent sufficient to vary the voltage across said circuit as the frequency of said circuit approaches one end of said range, and an energy transfer circuit coupled between the other of said electrodes and said frequency-determining circuit, the reactive constants of said transfer circuit being so proportioned that the responsiveness thereof varies with frequency at said one end of said range in a sense to compensate for the effect of said variation in voltage, thereby to render the output voltage of said oscillator more nearly uniform throughout said range.

5 5. An oscillator comprising a vacuum tube including input and output electrodes, a frequency-determining circuit coupled to one of said electrodes, said circuit including parallel-connected fixed capacitance means and at least one inductance element adjustable to vary the frequency of said circuit continuously over a wide range, said frequency variations incidentally varying the parallel impedance of said circuit in a sense to decrease the voltage across said circuit as the frequency of said circuit approaches the high-frequency end of said range, and an energy-transfer circuit coupled between the other of said electrodes and said frequency-determining circuit, the reactive constants of said transfer circuit being so proportioned that the responsiveness thereof varies with frequency at said one end of said range in a sense to compensate for the effect of said variation in voltage, thereby to render the output voltage of said oscillator more nearly uniform throughout said range.

10 6. An oscillator comprising a vacuum tube including input and output electrodes, a frequency-determining circuit coupled to said output electrodes, said circuit including parallel-connected fixed capacitance means and at least one inductance element adjustable to vary the frequency of said circuit continuously over a wide range, said frequency variations incidentally varying the parallel impedance of said circuit in a sense to decrease the voltage across said circuit as the frequency of said circuit approaches the high-frequency end of said range, and an energy-transfer circuit coupled between the other of said electrodes and said frequency-determining circuit, the reactive constants of said transfer circuit being so proportioned that the responsiveness thereof increases as the frequency of said frequency-determining circuit approaches the high-frequency end of said range, thereby to render the output voltage of said oscillator more nearly uniform throughout said range.

15 7. An oscillator comprising a vacuum tube including input and output electrodes, a frequency-determining circuit coupled to one of said electrodes, said circuit including a pair of fixed inductance elements and capacitance means all effectively in parallel, one of said inductance elements being adjustable to vary the frequency of said circuit continuously over a wide range, and an energy transfer circuit coupled to the other of said electrodes and including a third inductance element coupled to the other of said 20 pair of inductance elements.

25 8. An oscillator comprising a vacuum tube in-

cluding input and output electrodes, a frequency-determining circuit coupled to one of said electrodes, said circuit including a pair of fixed inductance elements and capacitance means all effectively in parallel, one of said inductance elements being adjustable to vary the frequency of said circuit continuously over a wide range, and energy transfer means coupled to the other of said electrodes and including a third inductance element coupled to the other of said pair of inductance elements to provide an effective coupling between said frequency-determining circuit and said energy transfer means which is independent of the frequency of said circuit.

9. An oscillator comprising a vacuum tube including input and output electrodes, a frequency-determining circuit coupled to one of said electrodes, said circuit including a pair of inductance elements and fixed capacitance means all effectively in parallel, one of said inductance elements being adjustable to vary the frequency of said circuit continuously over a wide range, and an energy transfer circuit coupled to the other of said electrodes and including a third inductance element coupled to the other of said pair of inductance elements and fixed capacitance, said energy transfer circuit being resonant at a frequency above the highest frequency of said range.

10. An oscillator comprising a vacuum tube including input and output electrodes, a frequency-determining circuit coupled to one of said electrodes, said circuit including a pair of inductance elements and substantially fixed capacitance means all effectively in parallel, one of said inductance elements being adjustable to vary the frequency of said circuit continuously over a wide range, said frequency variations incidentally varying the parallel impedance of said circuit in a sense to decrease the voltage across said circuit as the frequency of said circuit approaches the high-frequency end of said range, and an energy transfer circuit coupled to the other of said electrodes and comprising a third inductance element inductively coupled to the other inductance element of said pair and being resonant at a frequency above the high-frequency end of said range, the increased responsiveness thereof tending to compensate for the effect of said variation in impedance of said frequency-determining circuit, whereby the output voltage of said oscillator is rendered more nearly uniform throughout said range.

11. An oscillator comprising a vacuum tube including an input electrode, an output electrode, and a cathode, a frequency-determining circuit coupled to said cathode and said output electrode, said circuit including a pair of inductance elements and substantially fixed capacitance means all effectively in parallel, one of said inductance elements being adjustable to vary the frequency of said circuit continuously over a wide range, said frequency variations incidentally varying the losses in said circuit in a sense to decrease the voltage across said circuit as the frequency of said circuit approaches the high-frequency end of said range, and an energy transfer circuit coupled to said cathode and said input electrode and including a third inductance element inductively coupled to the other of said pair of inductance elements and being resonant at a frequency above the high-frequency end of said range, the increased responsiveness thereof tending to compensate for the effect of said variation in losses, whereby the output voltage of said oscillator is rendered more nearly uniform throughout said range.

12. An oscillator comprising a vacuum tube including input and output electrodes, a frequency-determining circuit coupled to said output electrodes, said circuit including at least one inductance element and substantially fixed capacitance means connected in parallel, said capacitance means comprising only the output capacitance of said tube and the stray capacitances of said circuit elements and connections, said inductance element being adjustable to vary the frequency of said circuit continuously over a wide range, said frequency variations incidentally varying the parallel impedance of said circuit to an extent sufficient to vary the voltage across said circuit as the frequency of said circuit approaches one end of said range, and an energy transfer circuit coupled between said input electrodes and said frequency-determining circuit, the reactive constants of said transfer circuit being so proportioned that the responsiveness thereof varies with frequency at said one end of said range in a sense to compensate for the effect of said variation in said parallel impedance, thereby to render the output voltage of said oscillator more nearly uniform throughout said range.

JOHN F. FARRINGTON.

CERTIFICATE OF CORRECTION.

Patent No. 2,165,468.

July 11, 1939.

JOHN F. FARRINGTON.

It is hereby certified that error appears in the printed specification of the above numbered patent requiring correction as follows: Page 4, second column, line 66, claim 7, strike out the word "fixed" and insert the same before "capacitance" in line 67, same claim; page 5, first column, line 3, claim 8, strike out the word "fixed" and insert the same before "capacitance" in line 4, same claim; and that the said Letters Patent should be read with this correction therein that the same may conform to the record of the case in the Patent Office.

Signed and sealed this 29th day of August, A. D. 1939.
